SILAS S. PUTNAM, OF DORCHESTER, MASSACHUSETTS.

Letters Patent No. 86,100, dated January 19, 1869.

IMPROVED CURTAIN-FIXTURE.

The Schedule referred to in these Letters Patent and making part of the same.

To all whom it may concern:

Be it known that I, SILAS S. PUTNAM, of Dorchester, in the county of Norfolk, and State of Massachusetts, have invented certain Improvements in Curtain-Fixtures, of which the following is a full, clear, and exact description, reference being had to the accompanying drawings, making part of this specification, in which—

Figure 1 is a perspective view of a window-frame, having my improved curtain-fixture applied thereto.

Figure 2 is a front elevation of the same.

Figure 3 is a section on the line $x x$ of fig. 2.

My invention relates to an improvement upon that class of curtain-fixtures in which a ratchet-wheel, at the end of the roll, is employed, in connection with a pivoted stop, which is operated by the cord used to raise and lower the curtain; and

My invention consists in a sliding stop, in combination with a wheel, provided with projections or notches, and secured to the end of the curtain-roll, the stop being so arranged that it can be easily operated by the cord in a convenient manner, when the curtain is to be raised or lowered, and will also retain the curtain at the desired height.

To enable others skilled in the art to understand and use my invention, I will proceed to describe the manner in which I have carried it out.

In the said drawings—

A represents a window-frame, to which are attached the brackets B C, which support the wooden curtain-roll D, to the right-hand end of which is secured a reel or pulley, the outer portion of which consists of a toothed wheel, E.

G is a sliding dog or stop, the point, *a*, of which is curved upward, and engages with the teeth of the wheel E, the stop being secured to the inside of the bracket C by pins, *b*, which are provided with heads, and pass through inclined slots, *c*, into the bracket.

The cord H, by which the curtain is raised or lowered, is secured to the spindle *d* of the reel, and passes through an eye, *e*, at the outer extremity of the sliding stop G, and it will be seen that a slight downward pull upon the cord H will cause the stop to slide in the direction of the red arrow, fig. 3, carrying the point *a* away from the teeth of the wheel E, when the cord may be allowed to slip through the fingers, the weight

of the curtain, as it descends, acting upon the cord, and producing sufficient tension thereon to retain the point *a* of the stop G out of contact with the teeth of the wheel E; but when the cord is suddenly slackened, or the hand is removed entirely therefrom, the stop will immediately fall back and catch one of the teeth of the wheel E, so as to retain the curtain at the desired height.

The above-described device is simple and durable, and may be easily operated, the curtain requiring no weighted tassel.

Instead of the slots being formed in the stop G for the reception of pins projecting out from the bracket C, their positions may be reversed, the slots being formed in the bracket; and the sliding stop may be so formed and arranged as to engage with either side of the wheel E, as may be found most desirable; and this wheel E may be provided with notches instead of projections, if preferred.

Instead of the slots *c* in the stop G being inclined, as above described, they may be made horizontal, without departing from the spirit of my invention, in which case, an outward pull upon the cord H would be required to bring the sliding stop back into contact with the teeth of the wheel E. I therefore prefer to make them inclined, as first described.

I do not confine myself to the use of slots and pins, as it is evident that the sliding stop G may be attached to the bracket by other means, if desired.

The left-hand end of the roll D fits into a metallic cap, I, provided with a pin, *f*, which fits into an open slot in the bracket B, so as to allow this end of the roll to be raised, when the pin *g*, at the opposite end, may be withdrawn from its bearing in the bracket C, and the roll taken down, if desired.

Claim.

What I claim as my invention, and desire to secure by Letters Patent, is—

A sliding stop, G, operated by the cord H, in combination with a wheel provided with projections or notches, substantially as and for the purpose described

SILAS S. PUTNAM.
